Primary Examiner — Jack Reickel*Assistant Examiner* — Christopher M Spivey(74) *Attorney, Agent, or Firm* — Saidman Design Law Group(57) **CLAIM**

The ornamental design for an electronic device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device with graphical user interface showing the claimed design;

FIG. 2 is a front view of another embodiment of an electronic device with graphical user interface; and,

FIG. 3 is a front view of another embodiment of an electronic device with graphical user interface.

The peripheral dashed broken lines illustrate a display screen or portion thereof, and form no part of the claimed design.
